UNITED STATES PATENT OFFICE.

JOSEPH V. KALER, OF COLUMBUS, OHIO.

DESIGN FOR A PICTURE-HOOK.

SPECIFICATION forming part of Design No. 30,719, dated May 9, 1899.

Application filed April 13, 1899. Serial No. 712,937. Term of patent 31 years.

To all whom it may concern:

Be it known that I, JOSEPH V. KALER, a citizen of the United States, residing at Columbus, in the county of Franklin and State of Ohio, have invented and produced a certain new and original Design for Picture-Hooks; and I do declare the following to be a full, clear, and exact description of the invention, such as will enable others skilled in the art to which it appertains to make and use the same.

The invention relates to a new and original design for picture-hooks; and it consists of a hook of the shape and configuration shown in the accompanying drawings, in which—

Figure 1 is a front view, and Fig. 2 is a side elevation.

The leading feature of the design consists in the vertical part 1, the lower end of which projects horizontally, as shown at 2, and is provided with a disk 3, and thence terminates in a hook 4.

What I claim is—

The design for a picture-hook, as herein shown and described.

In testimony whereof I have hereunto set my hand in presence of two subscribing witnesses.

JOSEPH V. KALER.

Witnesses:

C. M. SCHOFIELD,
J. H. SEARS.
